(57) **CLAIM**

The ornamental design for a container with pump, as shown and described.

DESCRIPTION

FIG. 1 is a perspective view of the container with pump of our design.

FIG. 2 is a left side elevation view thereof.

FIG. 3 is a right side elevation view thereof.

FIG. 4 is a front elevation view thereof, the rear elevation view being a mirror image thereof.

FIG. 5 is a top plan view thereof.

FIG. 6 is a bottom plan view thereof; and,

FIG. 7 is a left side elevation view of an alternate embodiment of the container with pump, the other views being the same.

1 Claim, 3 Drawing Sheets
